(57) **CLAIM**

We claim the ornamental design for a paper cup with fold top lid, as shown and described.

DESCRIPTION

FIG. 1 is a perspective view of a paper cup with fold top lid showing our new design with the fold top lid in the open position;

FIG. 2 is a perspective view thereof with the fold top lid in the closed position;

FIG. 3 is a front elevational view thereof with the fold top lid in the open position;

FIG. 4 is a front elevational view thereof with the fold top lid in the closed position;

FIG. 5 is a side elevational view thereof with the fold top lid in the open position;

FIG. 6 is a side elevational view thereof with the fold top lid in the closed position;

FIG. 7 is a top plan view thereof with the fold top lid in the open position;

FIG. 8 is a top plan view thereof with the fold top lid in the closed position; and,

FIG. 9 is a bottom view thereof with the fold top lid in the open position.
